UNITED STATES PATENT OFFICE

GEORGE H. PULSIFER, OF HAVERHILL, MASSACHUSETTS

DESIGN FOR A HEEL FOR WOMEN'S FOOTWEAR

Application filed March 27, 1933. Serial No. 47,610. Term of patent 3½ years.

To all whom it may concern:

Be it known that I, GEORGE H. PULSIFER, a citizen of the United States of America, residing in Haverhill, county of Essex, State of Massachusetts, have invented a new, original, and ornamental Design for a Heel for Women's Footwear, of which the following is a specification, reference being had to the accompanying drawing, forming a part thereof.

Fig. 1 is a rear elevation of a heel for women's footwear, showing my new design; Fig. 2 is a side elevation, and Fig. 3 is a bottom plan view of the same.

I claim:

The ornamental design for a heel for women's footwear, substantially as shown.

GEORGE H. PULSIFER.
